2,181,473

WATER-COOLED STOKER

Joseph S. Bennett, Merion, Pa., assignor to American Engineering Company, Philadelphia, Pa., a corporation of Pennsylvania

Application November 4, 1937, Serial No. 172,711

1 Claim. (Cl. 122—4)

This invention relates to furnace stokers, and more particularly to furnace stokers of the fluid cooled type.

In stokers of this type certain of the fluid conducting tubes of the cooling system associated therewith are protected, at least in part, from the heat of the furnace. Circulation of the fluid through such tubes therefore often becomes sluggish, causing overheating of the tubes, and ultimately, damage thereto.

One object of the present invention is to provide an improved circulatory system for the fluid cooled section of furnace stokers of the stated character which will eliminate the above mentioned difficulties.

Another object is to so arrange the riser connections for the fluid cooled section of stokers that they will be exposed directly to the heat of the furnace, thereby inducing rapid circulation in the system.

A further object is to arrange the riser connections of the fluid cooled system of the stoker in such a manner that they will serve the dual function of inducing rapid circulation in the system, and of cooling a portion of the walls of the furnace.

Other and further objects will become apparent as the description of the invention progresses.

Of the drawings:

Fig. 1 is a longitudinal sectional view taken through a stoker furnace showing a construction wherein the tubes forming the cooling medium for the tuyères, and the riser connections for the cooling section of the retorts, extend upwardly and form a portion of the front wall of the furnace.

Fig. 2 is an enlarged detail sectional view of the upper header shown in Fig. 1, and

Fig. 3 is an elevational view with a portion of the header broken away, taken substantially along line 3—3 of Fig. 2.

The drawings illustrate a construction wherein the boiler 56 of the furnace 57 is fired by a stoker 58 of the dump type. Boiler 56 comprises steam drums 59 and 60 connected by tubes 61, and a mud drum 62 which is connected to the steam drums by the usual banks of tubes 63. The inner bank of tubes 64 may be block covered at the lower end thereof, as shown at 65, and constitutes the bridge wall of the furnace. Stoker 58 is of the inclined grate underfeed type consisting of alternately disposed retorts 66 and tuyère rows 67. Each retort 66 has provided at the bottom thereof a series of feeding pushers 68, the lowermost of which rests upon a fuel supporting or dead plate

69. Mounted on a shaft 70, extending transversely at the lower, rearwardly disposed end of the stoker, are a series of dump plates 71. These plates are arranged in spaced relation with the lower ends of the boiler tubes 64 forming a passage 72 therebetween through which the refuse fed from the stoker may pass. Adjustable means for shaft 70 may be provided to vary the size of the discharge passage 72 if so desired.

Each tuyère row 67 of this construction has 10 also provided in cooling relation therewith one or more tubes 73. These tubes are bent upwardly, as shown at 74, so as to extend along the inner surface of the front wall 75 of the furnace, and terminate in a header 76. The lower ends of tubes 15 73 extend beyond the tuyère rows 67 and are bent downwardly, as shown at 77, and terminate in a header 78 disposed beneath dump plates 71. The dead plates 69 have also mounted in cooling relation therewith one or more tubes 79. The forwardly disposed ends of tubes 79 are connected 20 to a header 80 mounted in any suitable manner beneath the stoker, while the rearwardly disposed ends thereof are bent downwardly in parallel relation with the extended portions of tubes 73 and 25 also terminate at their lower ends in header 78. Header 80 is connected to header 76 by risers 81. These risers extend upwardly along wall 75 and may be disposed between the portions of the tubes 30 73 extending upwardly from the tuyère rows. Header 78 is connected to the mud drum 62 of the boiler by downtake connections 82, while header 76 is connected to steam drum 60 by tubes 83, the latter of which extending along the inner surface of the upper wall 84 of the furnace.

As shown more particularly in Figs. 2 and 3, the upper ends of risers 81 are connected to the corresponding tubes 83 by elbow connections 85. The enlarged end 86 of each elbow 85 telescopes over the upper end of its corresponding riser 81 35 and may be secured in position by any suitable means, such as by welding. The reduced end 87 of each elbow on the other hand simply abuts the inner end of a corresponding tube 83. By this construction proper circulation between the fluid 40 cooled section of the stoker and the boiler is assured.

It will be observed that the risers 81, the upper portions of the tubes 73, as well as the tubes 83, are directly exposed to the heat of the furnace, 50 and consequently relatively rapid circulation will be induced in the system.

While the embodiment herein shown and described is admirably adapted to fulfill the objects primarily stated, it is to be understood that the 55

invention is not to be limited thereto, since it may be embodied in other forms, all coming within the scope of the claim which follows.

What is claimed is:

- 6 In a furnace, the combination of a boiler, a stoker for firing said boiler, said stoker comprising alternately disposed retorts and tuyère rows, fuel supporting means provided at the bottom of each of said retorts and extending between adjacent tuyère rows, front, side and top walls for said furnace, a pair of fluid conducting tubes mounted in cooling relation with each of said tuyère rows, extensions for said tubes extending vertically along said front wall, a header mounted 10 interiorly of said furnace connected to the upper ends of said extensions, a series of tubes extending along said top wall connecting said header to

said boiler, one or more fluid conducting tubes mounted in cooling relation with each of said fuel supporting means, a second header connected to the lower ends of all of said tubes, means connecting said second header to said boiler, a third header connected to the upper ends of the tubes mounted in cooling relation with each of said fuel supporting means, risers connecting said third and first headers, said risers extending vertically along said front wall between pairs of said first mentioned tubes, and a plurality of connecting means mounted within said first mentioned header and establishing communication between said risers and certain of the said tubes extending along said top wall.

JOSEPH S. BENNETT.
